John Neil.
Design for a Floor Cloth Pattern.
Patented March 1, 1864.

J. D. Wright,
L. L. Brown

John Neil

UNITED STATES PATENT OFFICE.

JOHN NEIL, OF CLINTON, MASSACHUSETTS, ASSIGNOR TO WM. M. BRASHER
AND S. H. HERRIMAN.

DESIGN FOR A FLOOR-CLOTH PATTERN.

Specification forming part of Design No. 1,907, dated March 1, 1864.

To all whom it may concern:

Be it known that I, JOHN NEIL, of the town of Clinton, in the county of Worcester and State of Massachusetts, have invented or produced a new and original Design for Stamping or Printing Oil-Cloths; and I hereby declare the following to be a full, clear, and exact description of the same, reference being had to the accompanying drawings, which are lettered to correspond with and form a part of the specification.

In order that the public may fully understand my invention and those who are skilled in the mechanic arts be enabled to make the same, I will describe it as follows:

Letter A is an ornamental center of different colors on green or other suitable ground which forms the space between the woven plats B B' B² B³. These plats are formed of ornamental centers upon drab, brown, or other suitable colored ground, provided with borders d d' d² d³, having a red, yellow, or other

ground with a dark zigzag stripe through the center thereof, as shown at e e e e in the drawings. Letters c c are squares of white ground provided with heavy ornamental mosaic work, and letters c' c' are similar squares of ornamental mosaic upon red or other suitable ground. Therefore—

What I claim as novel and useful, and what I wish to secure by Letters Patent of the United States, is—

The arrangement and use of the different ornamental mosaic devices A and plats B B' B² B³, borders d d' d² d³, around the ornamental squares c c c' c', as set forth, and shown in the drawings.

In testimony whereof I hereunto subscribe my name in the presence of two witnesses.

JOHN NEIL.

Witnesses:

E. K. GIBBS,
CHILS. STEVENS.
